(57) **CLAIM**

The ornamental design for an outdoor musical instrument, as shown and described.

DESCRIPTION

The patent file contains at least one drawing executed in color. Copies of this patent with color drawings will be provided by the Office upon request and payment of the necessary fee.

FIG. 1 is a top, front perspective view of an outdoor musical instrument showing my new design according to a first embodiment;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a bottom, rear perspective view thereof;

FIG. 9 is a top, front perspective view of an outdoor musical instrument showing my new design according to a second embodiment;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top plan view thereof;

FIG. 15 is a bottom plan view thereof;

FIG. 16 is a bottom, rear perspective view thereof;

FIG. 17 is a top, front perspective view of an outdoor musical instrument showing my new design according to a third embodiment;

FIG. 18 is a front elevation view thereof;

FIG. 19 is a rear elevation view thereof;

FIG. 20 is a right side elevation view thereof;

FIG. 21 is a left side elevation view thereof;

FIG. 22 is a top plan view thereof;

FIG. 23 is a bottom plan view thereof; and,

FIG. 24 is a bottom, rear perspective view thereof.

The evenly dashed broken lines in the drawings illustrate portions of the outdoor musical instrument that form no part of the claimed design.

The red and white color on the cap portion of the outdoor musical instrument forms part of the claimed design; the
